UNITED STATES PATENT OFFICE.

ANDREW SCHECK AND WILLIAM H. FINFROCK, OF CHICAGO, ILLINOIS.

GAS-GOVERNOR.

No. 870,470.

Specification of Letters Patent.

Patented Nov. 5, 1907.

Application filed June 4, 1907. Serial No. 377,172.

To all whom it may concern:

Be it known that we, ANDREW SCHECK and WILLIAM H. FINFROCK, citizens of the United States, residing at Chicago, in the county of Cook and State of Illinois, 5 have invented certain new and useful Improvements in Gas-Governors; and we do hereby declare the following to be a full, clear, and exact description of the invention, such as will enable others skilled in the art to which it appertains to make and use the same.

10 Our invention relates to improvements in automatic gas governors.

It has for its object to provide a simple and comparatively cheap device of this nature which will give satisfactory results.

15 The invention consists in the features of construction and combinations of parts hereinafter described and specified in the claims.

In the accompanying drawing illustrating the preferred embodiment of my invention: Figure 1 is a central vertical sectional view of the governor. Fig. 2 is 20 a detailed view of the valve, and Fig. 3 is a detailed view of the toggle and adjusting screw connected thereto.

Referring more particularly to the drawing, 1 designates the casting comprising the body of the governor. Said body has a straight bore to receive the sliding tubular valve 2. The inlet passage 3 is at right angles to the valve while the outlet 4 is in line therewith. There is another tubular offset portion 5 of the body also arranged at right angles to the valve but above the inlet passage. To the end of said offset 5 is secured the casing 6 containing the diaphragm 7. Said casing is made in two parts fastened together at their edges by bolts 8. The edge of the diaphragm, which is preferably made 35 of German silver, is clamped with packing 9 between the edges of the parts of the casing. Said casing is secured to the offset 5 by screws 10 and the joint is packed as at 11. The cap 12 below the valve may be taken off to remove any foreign matter which may collect in the 40 body. The valve 2 has slots 13 cut in its wall opposite the inlet, and the body of the governor is bulged out around said slots to permit the gas to pass around and enter both of them. The upper end of said valve is open save for a cross piece 14 into which a pin 15 is 45 screwed. Said pin has a horizontal slot 16 in its head whereby it is connected to one end of a lever 17 arranged in the tubular offset 5 and pivoted to an extension of the inner part of the diaphragm casing. The other end of said lever is bent up and pivotally connected to a link or toggle 18. An adjusting screw 19 is swiveled to the toggle being let into a slot opening on the bottom of said toggle. Said screw passes through a nut 20 in the center of the diaphragm and extends beyond the casing where it may be grasped for operation.

50 The diaphragm is pressed by a coiled spring 21 partially inclosed in a hollow screw 22 adjustable in the outer

part of the casing and having an opening in its end through which the adjusting screw 19 extends. Said screw 22 is fitted with a lock nut 23 which is screwed against the casing to hold said screw in proper adjustment.

It will be noted that there are two means of adjusting the valve, namely by the screw pin 15 and the screw 19. The tension on the diaphragm may be adjusted by means of the hollow screw 22. In this way very fine 65 adjustments may be made to conform to the number of lights used and the pressure of the gas in the pipes. Experiment has shown that the use of our governor reduces the gas bill at least one-third. There is always enough leakage through the valve to act on the dia- 70 phragm which keeps the valve closed when not in use.

We claim:

1. A gas governor of the character described comprising a body or casing having inlet, and outlet ports, a valve arranged across said inlet port, an adjusting screw engaging 75 said valve and having a slot in its head, a diaphragm, and an intermediately pivoted lever connected at one end to said diaphragm and at the other end to the slot in the head of said screw.

2. A gas governor of the character described comprising 80 a body or casing having inlet and outlet ports, a valve arranged across said inlet port, a diaphragm, a pivoted lever connected at one end to said valve, a toggle connected to the other end of said lever, and a screw having swivel connection with said toggle and adjustably engaging the dia- 85 phragm.

3. A gas governor of the character described comprising a body or casing having inlet and outlet ports, a valve arranged across said inlet port, a diaphragm, a pivoted lever connected at one end to said valve, an adjustable screw 90 connected to the other end of said lever and to said dia- phragm, a coiled tension spring engaging said diaphragm, a hollow screw engaging the casing and partially inclosing said spring, the first mentioned screw extending through said spring and beyond said hollow screw for 95 operation.

4. A gas governor of the character described comprising a body or casing having inlet and outlet ports, a valve arranged across said inlet port, a diaphragm, a pivoted lever connected at one end to said valve, an adjustable screw 100 connected to the other end of said lever and to said dia- phragm, a coiled tension spring engaging said diaphragm, a hollow screw engaging the casing and partially inclosing said spring, the first mentioned screw extending through said spring and beyond said hollow screw for 105 operation and a lock nut on said hollow screw and adapted to engage the outside of the casing.

5. A gas governor of the character described comprising a body or casing having inlet and outlet ports, a slotted tubular valve adapted to move across said inlet port, a 110 diaphragm and a lever pivoted intermediate of its ends, one end of said lever being connected to said diaphragm and the other end connected to said valve.

In testimony whereof, we affix our signatures, in presence of two witnesses.

ANDREW SCHECK.
WILLIAM H. FINFROCK.
